J. NEMEC

REFRIGERATOR

Filed Oct. 29, 1923

UNITED STATES PATENT OFFICE.

JOSEPH NEMEC, OF CHICAGO, ILLINOIS.

REFRIGERATOR.

Application filed October 29, 1923. Serial No. 671,541.

To all whom it may concern:

Be it known that I, JOSEPH NEMEC, a citizen of the United States, and a resident of Chicago, in the county of Cook and State 5 of Illinois, have invented a new and useful Improvement in Refrigerators, of which the following is a full, clear, and exact description.

My invention relates to improvements in 10 refrigerators or ice boxes, and it consists in the combinations, constructions and arrangements herein described and claimed.

An object of my invention is to provide 15 an ice box or refrigerator which is primarily designed for use in dining cars, and in which the objection known as sweating is obviated.

A further object of my invention is to provide 20 a device of the type described, in which the water from the melting ice is prevented from entering the food chamber, and in which an efficient circulation of air is maintained.

A further object of my invention is to 25 provide a refrigerator in which the shelves are so arranged that they may be easily removed or replaced, as when it is desired to flush the refrigerator.

Other objects and advantages will appear 30 in the following specification, and the novel features of the invention will be particularly pointed out in the appended claims.

My invention is illustrated in the accompanying drawings, forming part of this 35 application, in which—

Figure 1 is a vertical section along the line 1—1 of Figure 2,

Figure 2 is a vertical section along the line 2—2 of Figure 1, and

Figure 3 is a section along the line 3—3 of Figure 1.

In carrying out my invention, I provide an outer casing 1, preferably of wood or other nonconducting material. The bottom 45 of this casing consists preferably of a layer of concrete 2 sloping in the manner shown in Figures 1 and 2. Secured to the outer walls 1 and embedded in the concrete are angle irons, such as that shown at 3 in Figures 1 and 2, and disposed on the angle iron 3 are angle irons 4 which support slats 5 surmounted by a sheet metal top 6, thus forming a slanting drain board, as shown in Figures 1 and 2.

Disposed above the drain board are angle

iron supports 7 for a grating 8. This grating is formed of wooden bars which are pivotally connected at 9 with other bars 10, disposed between the bars 8, so that when swung at right angles to them, it will provide a grating back of the ice 11 in the lower compartment, as well as a support 8 for the ice to rest upon. These gratings, as will be seen from Figures 1 and 2, are made in two sections, which are separately removable.

On the interior of the casing are vertically extending angle irons 12 and 13 respectively. In the corners of these angle irons are integral triangular-shaped webs 14, upon 70 which are mounted transversely extending angle irons 15, which are arranged to support metal shelves 16 having perforations 17, the edges of these metal shelves being turned 75 down to form flanges which rest on the angle irons 15.

In the drawings I have shown vertically extending wooden strips 18. On one side of these strips is a metal lining 19 which is perforated. On the opposite side of the vertically extending strips 18 is a series of slats 20, which have a portion bent away from the metal lining 19. The bent portion overhangs the upper end of the next lower adjacent slat, as will be clearly seen from the drawing. The upper ice compartment is provided with a grating 21, upon which the ice 22' is placed. One end of this grating is supported on an angle iron 22 which is secured to vertically extending irons 23. On the opposite side of the chamber are bent angle irons 24. These irons aid in supporting metal plates 25, 26 and 27, the plates 25 and 27 being spaced from the plate 26 85 by means of wooden spacing blocks or strips 28. Below the grating 21 is an inclined partition 29, while below the partition 29 is a substantially parallel plate 30. The partitions are spaced apart by means of strips 31 90 therebetween, and are secured in position in any suitable manner.

From the foregoing description of the various parts of the device, the operation thereof may be readily understood. In the ordinary dining car refrigerator, great inconvenience is experienced because of the fact that the ice in the upper compartment cools the partition just below it, which in the ordinary construction forms the ceiling of 100 the food compartment. This results in 110

"sweating" or in the collection of moisture, which may drip down on the food and ruin it.

In the present construction, this is obviated. It will be noted that ice is placed in the lower compartment through the door 32, while food may be placed in the intermediate compartments through the door 33. The food being warmer, tends to cause an upward current of air. This current reaches the inclined portion 26^a of the partition 26, and is deflected in the manner shown by the arrow. The partition 26 is provided with an opening 26^b, and the partition 25 has an opening 25^b. A current of air may pass through these openings 26^b and 25^b into the upper compartment. As the ice in the upper compartment melts, it drips down on the partition 29 which is inclined, and the water runs to a position where it will drip down on the slats 20, that is to say, away from the food chamber. Part of the current of air, however, will fall down between the upper partitions 29 and 30. Any moisture or sweating on the partition 29, or any dripping from such sweating will be received by the partition 30, and such moisture will be carried out, as shown by the arrow. In other words, by providing a double wall between the upper ice chamber and the food chamber, and also by providing means whereby the air may carry away the moisture in this passage, any danger of sweating is positively obviated, so that the food in the food chamber is always kept dry, as far as any dripping from the ordinary condensation of moisture is concerned. The water passes down, dripping from one slat to another, while at the same time there is provision for the entrance of air through the partition 19. This tends to permit a free circulation, which is of course desirable, but the arrangement is such that the water cannot enter the compartments. It falls to the bottom and is carried by the drain board out through a drain opening 34 in a door 35, which may lead to any suitable source of discharge.

It will be noted that the grids or grating 8 and 21, as well as the shelves 16, are in two sections. Ordinarily, a shelf which is in one section must be tilted to go through a door which is narrower than the width of the shelf. In the present instance, it is not necessary to tilt the shelves or the grates, since one-half of the shelf may be lifted independently and passed out through the

door, without tilting. This renders the removal or the replacement of the shelves or grates easy, as for instance, when the refrigerator is being flushed. 60

When it is desired to flush the refrigerator, the shelves may be removed, as stated, and such flushing can take place, and the provision of the swing door 35 is such that it will open to drain the refrigerator, when an abnormal flow of water occurs, as where the refrigerator is being flushed with a hose. 65

It will thus be seen that I have provided a device in which the ordinary sweating is 70 obviated. The construction is such that the refrigerator will stand more usage, due to the fact that the parts are secured together firmly. 75

I claim:

1. A refrigerator comprising an outer casing, a food compartment having a perforated wall spaced from said outer casing, an ice compartment disposed above said food compartment, a double walled inclined partition separating said food compartment from said ice compartment, said ice compartment draining into the space between the casing and said perforated wall, and a series of slats disposed between said casing and said perforated wall, the lower ends of the slats being bent toward the casing to overhang the upper ends of the adjacent lower slats, whereby the water from the ice chamber is prevented from entering through 80 the openings in the perforated wall, while air is permitted to so enter. 85

2. A refrigerator comprising an outer casing, a vertically disposed perforated partition within the casing, the space between the partition and the adjacent wall of the casing constituting a water drain, a series of slats having portions bent toward the outer casing for preventing the entrance of water through the perforated partition, the space 95 on the opposite side of said perforated partition constituting a food chamber, an upper ice chamber, an inclined double walled partition between said upper ice chamber and said food chamber, an air passage extending 100 upwardly from said food chamber and having communication with said ice chamber and with the space between the walls of said inclined partition, and means for conducting the water from the melting ice and condensed moisture between the walls of the inclined partition into the water-drain. 105

JOSEPH NEMEC.
